RADIATOR

Chester J. Sucharski, South Milwaukee, and
Arthur W. Lees, Racine, Wis.

Application November 16, 1934, Serial No. 753,334

1 Claim. (Cl. 257—136)

This invention appertains to heat exchange devices, and more particularly to a novel radiator, the principles of which are capable of general application.

5 One of the salient objects of our invention is to provide novel means for constructing a radiator for either heating or cooling purposes, having novel core units for insuring a quick and uniform exchange of heat between liquids and 10 gases.

10 Another important object of our invention is to provide a radiator in which the heat exchange core can be readily built up, assembled in and associated with any desired type of shell, or 15 casing.

15 A further object of our invention is to provide a radiator including a core embodying a plurality of interfitting rings, or cups, adapted to be soldered or otherwise connected together, 20 having annular outstanding heat absorbing flanges on their outer faces, and inwardly directed heat dissipating fins on their inner faces, the fins being staggered relative to one another for forming a tortuous passage for the air 25 through the core so as to insure the rapid transmission of heat thereto.

25 A further object of our invention is to provide inwardly directed fins on the interfitting rings, or cups, arranged in staggered relation, 30 the fins having openings therethrough in alignment with spaces between the fins of adjacent rings, whereby to permit a maximum flow of air around and through the fins.

35 A further object of our invention is to provide a radiator including a core having a plurality of interfitting rings provided with annular stop shoulders thereon to form a snug fit with adjacent rings, the rings having annular outstanding flanges on one of their edges, and 40 inwardly directed fins on their other edges.

45 A still further object of our invention is to provide a novel radiator of the above character, which will be durable and efficient in use, one that will be simple and easy to manufacture, and one which can be placed upon the market at a reasonable cost.

50 With these and other objects in view, the invention consists in the novel construction, arrangement and formation of parts as will be hereinafter more specifically described, claimed and illustrated in the accompanying drawing, in which drawing:—

55 Figure 1 is a bottom plan view of the radiator with the shell in horizontal section, one of the rings of one core unit being shown broken away

to illustrate the arrangement of the fins of the rings relative to one another.

Figure 2 is a detail vertical section taken on the line 2—2 of Figure 1, looking in the direction of the arrows.

5 Referring to the drawing in detail, wherein similar reference characters designate corresponding parts throughout the several views, the letter A generally indicates our improved radiator which comprises a shell, or casing, 5 having 10 a plurality of core units 6 mounted therein.

The shell 5 can be of any desired construction and shape, and, as shown, the same includes top and bottom walls 7 and 8, end walls 9 and side walls 10. The bottom wall 8 can be made separate from the body portion of the shell and secured thereto in any preferred manner. The end walls 9 can be provided respectively with inlet and outlet nipples 11 and 12 for permitting the flow of liquid through the shell.

20 Each of the core units 6 embodies a plurality of interfitting rings 15 which form the salient feature of our invention. These rings are preferably formed from light sheet metal and stamped or pressed into their desired form, but it is to be understood that the rings can be molded without departing from the spirit of our invention. The metal from which the rings are formed is preferably of such a nature as to 25 rapidly conduct heat.

25 Each of the rings, or cups, 15 includes an annular body, or side wall, 16, and this body, or wall, is offset intermediate its ends to provide an annular stop shoulder 17. One edge of each 30 ring is provided with an annular outstanding flange 18, which forms a means for absorbing heat from the liquid flowing through the shell. The other edge of the ring is provided with a plurality of equidistantly spaced radially disposed fins 19. All of the fins are provided with openings 20 therethrough.

35 The rings are fitted one within the other, and the shoulders form seats for adjacent rings. The rings preferably have a press fit, and the same can be soldered or welded together, if preferred.

40 In assembling the rings to form a core unit, the fins 19 thereof are staggeredly related so as to form a tortuous pass for the air flowing therethrough. Care is taken to have the openings 20 of one ring in alignment with the spaces between the fins of the next ring. Thus, this not only allows the flow of air around the fins, but also permits the flow of air through the fins.

45 As shown in Figure 2, the bottom plate, or 50

wall, 8 is provided with a plurality of openings 21 for the core units, and these openings 21 are in direct alinement with openings 22 formed in the top wall 7. An annular bead, or flange, 5 23 is formed around the openings 21 to provide a seat for the core unit, and the annular flange of the lowermost ring fits snugly against the inner face of the plate 8 around the flange 23.

The walls of the openings 22 can be rabbeted 10 to provide shoulders 24 for receiving the top-most rings of the core units, and, if desired, the top and bottom rings of the core units can be soldered or welded to the walls of the shell.

Obviously, as the water or other liquid flows 15 through the shell, the same will circulate around the different core units which are also staggeredly arranged. The water flowing between the annular flanges 18 will permit these flanges 20 to quickly absorb the heat from the water and transmit the same to the fins, where the heat

is dissipated to the air flowing through the core units.

It has been found that a radiator constructed in accordance with our invention is cheap to manufacture and assemble, and is highly efficient in use.

Changes in details may be made without departing from the spirit or the scope of our invention, but what we claim as new is:—

A core unit for radiators comprising a plurality of interfitting rings, each ring including a body having an annular, outstanding flange formed at one end and an inwardly directed flange formed at the opposite end, means carried by said body forming a stop for the adjacent 15 ring to equidistantly space said flanges, the inner flanges of the rings being staggeredly related to one another and provided with aligned openings.
